Primary Examiner — Mojtaba Tehrani(74) *Attorney, Agent, or Firm* — Fox Rothschild LLP(57) **CLAIM**

The ornamental design for a shooting target assembly, as shown and described.

DESCRIPTION

FIG. 1 is a front view of a shooting target assembly.

FIG. 2 is a front perspective view of the shooting target assembly.

FIG. 3 is a right side view of the shooting target assembly.

FIG. 4 is a left side view of the shooting target assembly.

FIG. 5 is a bottom view of the shooting target assembly.

FIG. 6 is a top view of the shooting target assembly.

FIG. 7 is rear view of the shooting target assembly.

FIG. 8 is front perspective view of the shooting target assembly; and,

FIG. 9 is a rear perspective view of the shooting target assembly.

In the drawings, the broken lines shown in FIGS. 1-9 indicate portions of the article not claimed, and form no part of the claimed design.

1 Claim, 9 Drawing Sheets(56)
